UNITED STATES PATENT OFFICE.

SPENCER C. CARY, OF BROOKLYN, NEW YORK, ASSIGNOR TO CARY MANUFACTURING COMPANY, OF BROOKLYN, NEW YORK, A CORPORATION OF NEW YORK.

METHOD OF AND MEANS FOR SEALING PACKAGES.

1,309,115.

Specification of Letters Patent.

Patented July 8, 1919.

Application filed January 4, 1918. Serial No. 210,340.

To all whom it may concern:

Be it known that I, SPENCER C. CARY, a citizen of the United States, residing at the city of New York, borough of Brooklyn, 5 county of Kings, and State of New York, have invented a certain new and useful Method of and Means for Sealing Packages, of which the following is a specification.

This invention is a method of and means 10 for sealing packages of various kinds, such as packing boxes, shooks, bundles of shingles and numerous other kinds of merchandise packages.

In the art of shipping packages it is usual 15 to apply a binder of one form or another to a shipping package, such as a metal strap or a wire band; further, it is customary to attach the metal strap by numerous nails to a wooden packing box or shook; further, it 20 is not unusual to use a metal seal in connection with a band to afford additional security in the transportation of the package, and in some instances the wooden box has been provided with a kerf or groove in order 25 to seat a wire band.

The object of this invention is to provide 30 for the application of a band to a shipping package in an expeditious and easy manner, and so that the band will be drawn so taut as to embed itself in the material of the 35 packing box, shook, or other package, thus precluding any tendency of the band to slip along the package or to become displaced accidentally thereon. The band is applied 40 to the package so that it binds said package in a way to afford added security thereto, and thus minimize the breakage of said package when subjected to rough handling. Furthermore, the band is not removable 45 easily from the package in order to gain access to the contents thereof, but should this condition arise, the band cannot be replaced in all respects similar to the condition prior to such removal, thus affording means for detecting the unwarranted entry 50 to the box or shook.

An important feature of my invention is the union between the meeting ends of the band so as to afford an efficient seal, thus 55 precluding the ready detachment of the band and a like entry of the packing case or box.

Accordingly, the problems to be solved are, first, the application of the band under 55 tension to the package, and, second, the

union of the meeting ends of the band while in a taut condition, such union affording a sealed condition for said meeting ends as well as a secure anchorage for the band.

The invention comprises a method of sealing a band around a shipping package consisting of the following steps:—first, stretching a band into contact with the package so as to bind its parts and to partially embed said band into the material of the package, particularly at the corners thereof, the end portions of the band being slack or free from tension and said slack end portions being positioned inlapping order; second, positioning a sealing, anchoring or retaining member into engagement with the free slack ends of the band; third, bending the free ends of the band into locking engagement with said sealing, anchoring or retaining member, and, fourth, relaxing tension on the band in order that the locked ends of the band will exert a pull upon the sealing, anchoring or retaining member.

Because of its tensile strength and also 80 by reason of its economy of manufacture, it is preferred to use wire as the material for the band, although in some instances I may use a material other than wire.

The sealing, anchoring or retaining member 85 may be embodied in various constructional forms, but I have found that such a member constructed for mechanical attachment in an easy manner to the shipping package is well adapted to meet the requirements of the invention. Such a member 90 comprises a body portion and a plurality of attaching flanges extending from said body portion, said attaching flanges being formed with one or more spurs and said flanges being 95 provided with transverse openings or slots through which the free slack ends of the bands are adapted to be passed prior to driving the spurs into the package and before tension is relaxed on the band.

This invention is characterized by numerous 100 functions and advantages in the art of shipping packages, among which are the facility and ease of application of the band to the package; the band is applied and held tightly into contact with the package so as to bind it securely and at the same time preclude the band from slipping upon the package; the ends of the band are securely fastened in a manner to effectively 105 110

seal the same, thus precluding tampering with the band without detection, and the sealing and anchoring means are substantially flush with the package or in flat contact therewith, thus enabling the sealed packages to be stacked or piled one upon the other in a manner to avoid tilting or inclining the packages, whereby any number of the sealed packages can be piled without 10 toppling them over.

In the drawings,

Figure 1 is a side elevation illustrating the operation of stretching the band so as to place the major portion thereof under tension, the end portions of said band being slack.

Fig. 2 is a view similar to Fig. 1 with the retaining or anchoring means positioned in contact with the lapping end portions 20 of the band while they are in a slack condition.

Fig. 3 is an elevation similar to Figs. 1 and 2, but showing the operation of the band stretching device so as to place the 25 band under tension, the anchoring or retaining device being ready for driving into the material of the package.

Fig. 4 is a plan view of a portion of a shipping package with the wire band applied thereto and with the anchoring or retaining device in position for driving into the package.

Fig. 5 is a sectional view of the package with the band applied thereto and with the 35 anchoring or retaining device driven into the package prior to bending or looping the end portions of the stretched band into locking engagement with the anchoring or retaining device.

Fig. 6 is a plan view of a portion of the package with the band and the anchoring or retaining device, showing the final operation.

Fig. 7 is a detail perspective view of the 45 retaining device or anchor.

A band A is stretched so tightly around a shipping package B that said band becomes embedded into the material of the shipping package, particularly at the corners thereof. To effect the desired stretching of the band a device of the form shown in Figs. 1, 2 and 3 is employed, but it is to be understood, first, that no claim is made herein to the particular device illustrated 50 in said figures, and, second, that any equivalent device for stretching the band may be employed. The band stretching device is shown as a power-operated screw C, a plurality of co-operating crossheads D, E, a 55 guide member F and band-gripping clamps D', E', carried by the respective heads D, E. As shown, the screw of the stretching device is provided with a continuous thread, although it is apparent that a right and left 60 threaded screw may be employed in connec-

tion with the two heads D, E in order to more rapidly impart the desired adjustment to said heads when the screw is rotated. The single threaded screw works loosely in a bearing of the head D, and has threaded 70 engagement with a nut (not shown) of the head E, whereby the rotation of the screw effects a relative movement between the two heads.

The screw spindle is provided at one end 75 with a hand crank c for its convenient operation. The guide rod F is attached at one end to the head D and is fitted loosely to the head E in order to direct the movement of the head E and to retain said head in a 80 parallel relation to the companion head D. The band-gripping clamp carried by each head is shown as having a pivotal connection with said head, said pivot being afforded by a pin d. The clamp is movable relatively 85 in the head, the lower part of which head constitutes one member of a grip, the other member of which grip is afforded by the lower part of the clamp. The clamp is adapted to be tightened upon the band A 90 by manipulating a thumb screw e, but in the preferred form of the instrument the clamps D', E' are cam-actuated so as to render them automatic in the work of gripping the band upon the rotation of the screw 95 spindle.

Fitted loosely upon the spindle are cam members G which are in contact with the upper part of the clamp D' or E', and upon the rotation of the screw in one direction 100 this cam member is actuated by said screw so as to turn the clamps D' E' on the pivots afforded by the pins d in the required direction to grip the band.

The anchoring or retaining device employed in my invention is illustrated at I in detail in Fig. 7 of the drawings, said device serving the purposes of a seal in coupling and locking the meeting ends of the band. The device comprises a body portion h, depending flanges i, and spurs j, the whole being composed of a single piece of metal and struck up from sheet metal of the required gage. The body portion h is a flat piece of metal from opposite sides of which 110 extend the flanges i. These flanges are cut away so as to produce the spurs j, and in the flanges are provided openings or slots k.

The band A is composed, preferably, of wire, for the reason that this material possesses the required tensile strength to stand stretching around the packing case, and it is economical of manufacture. It is to be understood that the invention is not limited to the use of wire as the band, for the reason 120 that other material, such as box strapping may be employed for this purpose.

When it is desired to apply a band to a shipping package of one form or another, such as a packing case, a shook, or a bundle 130

of material, the wire band is placed loosely around the case, as illustrated in Fig. 1. The stretching device is positioned upon the top of the case so that the two ends of the band are between the heads D E. The band is passed between the lower ends of the heads D E and the clamps D' E', after which the thumb screw *e* may be tightened in order to make the clamps and the heads grip the band, but this manual manipulation of the thumb screws is not necessary, for the reason that the rotation of the screw spindle C will actuate the cam members G in order to move the clamps D' E' into gripping engagement with the band. The continued rotation of the screw spindle moves the heads D E toward each other, thus stretching the band tightly around the shipping package, and in fact the band may be stretched to the point where it becomes partially embedded in the material of the shipping package, particularly at the corners thereof. This operation of exerting a drawing pull upon the two ends of the band is conducted while the meeting ends of the band are in a slack condition, and this is advantageous for the reason that it allows the anchoring or retaining device I to be easily positioned over the loose or slack ends of said band, the remainder of which band is under the required tension. The operator lifts one slack end of the band sufficiently for said end to be thrust through the slots *k* in the retainer, after which the retainer is slid along the band for a sufficient distance to clear the extremity of the other slack end, whereupon the second slack end of the band is lifted and the retainer is slipped in a reverse direction so that the second end will be received in the slots or openings *k*. The retainer is now in contact with the two slack ends of the band, and said retainer may then be adjusted as in Figs. 2 and 3 to a desired position upon the case, the next step in the operation consisting in driving the retainer into the material of the case, for which purpose the spurs *j* and the flanges *i* will readily penetrate into or become embedded in the wood of the case or the material of the pack-

age, see Fig. 5, whereby the retainer is attached or anchored firmly on the case. The operator now proceeds to bend one end of the band A in one direction round a flange *i* of the retainer, as indicated at *a* in Fig. 6, whereas the other end of the band is bent in an opposite direction and around the other flange *i* of the retainer, as at *b* in said Fig. 6, thus locking the two slack ends of the stretched band firmly to the retainer.

The several operations of applying the retainer to the band, adjusting the retainer into contact with the two ends of the band and to a desired position upon the case, driving the retainer into the case and locking the ends of the band to the retainer are

all conducted easily and quickly while the major part of the band is in a stretched condition, for the reason that the stretching device is practically out of the way of the operator while performing said operations. The retainer having been positioned, attached to the case and locked with the ends of the band, the operator now turns the screw to release the clamps or manipulates the thumb screw *e* for the same purpose, thereby relaxing the pull on the stretched band, the latter remaining under the tension initially applied thereto, and said stretched band applying tension to the retainer which is anchored on the shipping package.

The retainer and the coupled ends of the band occupy a very compact or even a substantially flush relation with the package, there being no protruding surfaces which are liable to catch in other packages, or which in any way will interfere with the operation of piling or stacking one shipping package upon another. The meeting end portions of the band are covered and substantially concealed by the plate of the retainer, and as the wire band is comparatively stiff, the loops or bent ends *a b* cannot be pulled away or displaced from engagement with the retainer without detection, said retainer serving all the purposes of a seal so as to preclude unauthorized persons from attempting to tamper with the contents of the package.

Having thus fully described the invention, what I claim as new and desire to secure by Letters Patent is:

1. In the art of binding shipping packages, the improvement which consists in stretching a band for the major part of its length so tightly around the package as to embed said band into the material of the package, the end portions of the band being slack, attaching a sealing member to the slack end portions of said band, and applying the tension of the stretched portion of the band to the sealing member by relaxing the drawing strain or pull applied to said band.

2. In the art of binding shipping packages, the improvement which consists in exerting a drawing pull upon a band so as to stretch it tightly around the package and embed said band into the material of said package at the corners thereof, the end portions of said band being slack and free, whereas the remainder of the band is under tension, attaching a sealing member in a fixed relation to the package and into engagement with the slack end portions of the band, attaching said slack end portions of the band to the sealing member, and relaxing the drawing pull upon the major part of the band.

3. In the art of binding shipping pack-

- ages, the improvement which consists in exerting a drawing pull upon a band so as to stretch it tightly around the package, the end portions of said band being slack and free whereas the remainder of the band is under tension, positioning a sealing member into engagement with the slack end portions of the band, attaching the sealing member to the package, thereby anchoring the sealing member, fastening the slack end portions of the band to the anchored sealing member, and relaxing the drawing pull upon the major portion of the band so that the tension of the band is applied to the anchored sealing member.
4. In a device of the class described, the combination with a binder under tensional strain, of a sealing device adapted to be anchored in a fixed position on the package to be sealed, the end portions of said binder being bent into interlocking engagement with said sealing device.
5. In a device of the class described, the combination with a band applied under tension to a shipping package, of a retainer or anchor, the respective end portions of said band having interlocking engagement with said retainer or anchor.
6. In a device of the class described, a retainer provided with means for fixing the same to a package, combined with a band the end portions of which are interlocked with said retainer.
7. In a device of the class described, a retainer provided with spurs for attaching the same to a package, combined with a band the end portions of which are partially concealed by said retainer and are locked thereto.
8. In a device of the class described, the combination of a band the end portions of which are positioned in lapping relation, and a retainer in contact with said lapping end portions, the latter being bent into locking relation to the retainer.
9. In a device of the class described, the combination of a band the end portions of which are positioned in lapping relation, and a retainer provided with slotted flanges through which are passed the end portions of said band, each end portion of said band being bent into locking engagement with said retainer.
10. In a device of the class described, a retainer provided with spurs and with slots or openings, combined with a band the end portions of which are passed through the slots or openings so as to bring said end portions into lapping relation to the retainer.
11. In a device of the class described, a slotted retainer having spurs for attachment to a package, combined with a band the end portions of which pass through the slots and are looped into locking engagement with said retainer.
12. In a device of the class described, a retainer comprising a body portion, attaching spurs extending from the body portion and affording means for locking engagement with a band, and openings through which the end portions of said band are adapted to be passed.
13. In a device of the class described, a retainer struck up from a single piece of metal and comprising a body portion, flanges extending from said body portion, spurs protruding beyond the flanges, and openings in said flanges.
14. In the art of binding shipping packages, the improvement which consists in stretching a band for the major part of its length around said package so as to leave the end portions of said band free and slack, and twisting the slack free ends of the band into locking engagement with an anchor while said band is under tension so as to anchor said ends and retain the band around the package.
- In testimony whereof I have hereunto signed my name.

SPENCER C. CARY.
